UNITED STATES PATENT OFFICE.

LEWIS A. McDOWELL, OF LUVERNE, MINNESOTA.

SPARK-PLUG.

1,196,566.

Specification of Letters Patent. Patented Aug. 29, 1916.

Application filed November 9, 1914. Serial No. 871,140.

To all whom it may concern:

Be it known that I, LEWIS ANDREW McDOWELL, a citizen of the United States, residing at Luverne, in the county of Rock, State of Minnesota, have invented certain new and useful Improvements in Spark-Plugs; and I do hereby declare the following to be a full, clear, and exact description of the invention, such as will enable others skilled in the art to which it appertains to make and use the same.

This invention relates to a spark plug.

An object of the invention is to so construct the device that when the engine makes its compression stroke the gas compressed within the plug is ignited and forced outwardly into the main compression chamber and thus a more powerful explosion is obtained.

A further object of the invention is to so construct the device that the length of the spark may be varied at will.

A further object of the invention is to provide for the removal and replacing of the upper electrode so that the same may be cleaned and replaced in such position that the spark between the electrodes will always remain constant.

A further object of the invention is to provide for the locking of the lower electrode in a predetermined position.

A further object of the invention is to make provision in the device for keeping the carbon from short circuiting the plug.

A further object of the invention is to so construct and arrange the electrodes that irrespective of the warping caused by the heat within the cylinder the movable electrode will be arranged above the stationary electrode so that the spark will not be distorted.

With these and other objects in view, such as will appear as the description progresses, my invention comprises the combination and arrangement of parts as set forth in and falling within the scope of the appended claims.

Referring to the drawing: Figure 1 is a longitudinal sectional view of my device. Fig. 2 is an elevational view of the inner core or insulator. Fig. 3 is a detail of the stationary electrode carrier. Fig. 4 is a sectional view on line 4-4 of Fig. 1.

Referring to the drawing wherein like

parts are indicated by like characters 55 throughout the several views:—

My device comprises a shell 5 which is threaded on its lower end, as at 6, so that it may be readily screwed into the proper opening in a combustion cylinder. This shell 60 5 has a hole 7 extending therethrough, which hole is threaded at its lower end, as at 8.

Detachably connected with the lower end of the shell 5 on the screw threads 8 is a split collar 9, the formation of which is 65 shown in Fig. 3. Depending from this collar is a U-shaped member 10 having an upwardly extending electrode 11 mounted in the bight portion thereof. This collar is split in order that after it has been engaged 70 with the threads 8 it will bind on the said threads and thus the rotation of the electrode 11 will be prevented, it being of course understood that the collar will possess a certain amount of resiliency to cause the 75 binding action.

In order that an upper electrode may be properly mounted with relation to the lower electrode 11, I have enlarged the hole 7 adjacent the upper end of the shell 5 so that 80 a shoulder 12 is provided on which is a packing ring 13. Resting on this packing ring and extending downwardly into the hole is an insulating barrel 14 which is in spaced relation to the inner wall of the 85 said shell 5. This barrel has an upwardly extending shank portion 15 which is likewise in spaced relation to the shell. This barrel is maintained in proper position by a jam nut 16 pressed on a shoulder 17 on the 90 said barrel but being insulated therefrom by suitable material 18.

Extending longitudinally through this barrel 15 is a hole 19. The lower end of this hole is enlarged, as at 20, and is of triangular formation. The hole is still further enlarged adjacent the lower end thereof forming a chamber 21 and a shoulder 22 between the chamber and the portion 20.

Removably mounted in this hole 19 is a 100 rod 23 having an enlarged triangular portion 24 thereon, which fits into the portion 20 of the hole 19 but is of slightly lesser diameter. A packing material 25 is placed in this portion 20 so as to prevent the escape of gases from the cylinder upwardly through the hole 19 around the rod 23. Below this triangular portion 24 is a collar 26

which bears against the shoulder 22 in the manner shown in Fig. 1.

Extending downwardly from this collar is an electrode 27 which normally is in alignment with the electrode 11, but the end of which is in spaced relation to the end of the said electrode 11.

The upper end of the rod 23 is screw threaded and has a cap 28 thereon and an 10 adjusting nut 29 by means of which nut and cap the distance between the electrodes may be varied.

In order that carbon deposited may be prevented from caking entirely about the 15 outer surface of the barrel 14 and thus short circuiting the device, I have provided a circular groove 30 adjacent the lower end thereof in which groove is mounted a split collar 31, the said collar being mounted so 20 that it may have rotative movement with relation to the barrel in the said groove and also vertical up and down movement with relation to the barrel, thus effectively preventing the caking of the carbon in a continuous sheet between the said barrel and the shell 5, the motion being caused by the 25 vibration of the engine.

From the foregoing description it may be readily observed that should the lower electrode 30 become caked with carbon after continued use, the said electrode may be bodily removed by unscrewing the collar 9, and it may then be replaced and held in such position because of the fact that it is split and 35 resilient which causes the said collar to grip this portion of the shell 5. Should it be desirable to remove the upper electrode for any reason whatsoever this may be accomplished by unscrewing the nut 16 and lifting 40 the electrode together with the barrel 14 bodily from the shell 5, this electrode may then be replaced and the shoulder thereon will contact with the shoulder 12 in the shell 5 to positively position the electrode point 45 27 in the same relation to the electrode 11 that it bore before being displaced.

Furthermore I have provided a spark plug wherein the possibility of short circuiting being caused by the carbon deposit 50 will be obviated by the use of a loosely mounted collar on the barrel which will

prevent the formation of a continuous sheet of carbon between the barrel and the shell, furthermore I have so constructed the device that should the movable electrode become warped by the action of the heat in the cylinders the spark will not be distorted by the said warping inasmuch as a portion of the electrode will be kept in alignment with the portion of the stationary electrode. 55 60

While I have illustrated and described a particular embodiment of my invention, I have merely done so for the sake of convenience and I do not wish to be limited to that particular embodiment as it is obvious that numerous changes may be made in the details of construction thereof without in any way departing from the spirit of the invention or without exceeding the scope of the appended claim. 70

What I claim is:—

In a spark plug, a shell having a longitudinally extending hole therein, an insulating barrel extending into the shell and in spaced relation to the wall thereof, the said barrel having an annular recess encircling the same adjacent its lower end, electrodes located below the insulating barrel, and a split collar, of slightly less width than the recess, mounted in the recess and adapted to move upon the vibration of the plug to prevent the forming of a continuous sheet of carbon on the face of the barrel, the said collar being rectangular in cross section whereby sharp edges are provided and being of greater inside diameter than the diameter of the portion of the insulating barrel which it encircles whereby upon the vibration of the plug and the movement of the collar, the axis of the latter will assume an angular position with relation to the axis of the barrel and the sharp edges of the collar will engage the adjacent portion of the face of the barrel and cut the carbon therefrom. 85 90 95

In testimony whereof, I affix my signature, in the presence of two witnesses.

LEWIS A. McDOWELL.
